TELEPHONE REPEATER

William Hennick Martin, Chappaqua, N. Y., assignor to American Telephone and Telegraph Company, a corporation of New York

Application October 28, 1933, Serial No. 695,678

8 Claims. (Cl. 179—170)

This invention relates to two-wire telephone repeaters, and more specifically to repeaters of the so-called directional type in which an attenuation pad is transferred from one side of the repeater to the other by a voice-operated relay, in accordance with the direction of arrival of speech currents.

It is an object of the invention to limit the circulating currents through the repeater due to impedance unbalance between the lines and their respective networks, thus permitting the repeater to give a larger gain than would otherwise be possible under the line balance conditions obtainable. A further object is to improve the operation of the voice-operated system by increasing the operating differentials without increasing the losses to speech. A third object is to improve the discrimination of the device against false operation due to noise. Another object is to decrease the loss suffered by voice currents which are too weak to affect the voice-operated mechanism.

The principle of the directional repeater is described in a patent application, Serial Number 687,880, filed by L. G. Abraham and D. Mitchell on September 1, 1933, and another application, Serial Number 687,874, filed by B. F. Lewis and J. L. Merrill, Jr., on September 1, 1933, both of which applications are assigned to the same assignee as the present one. Briefly stated, such a repeater is of the ordinary 22-type, with the addition of a voice-operated system which makes an increase in the gain of one side of the repeater, and a corresponding decrease in the gain of the opposite side, in accordance with the direction of arrival of voice currents at the repeater. A net loss can thus be maintained in the path of circulating currents within the repeater, while a net gain is provided in the direction in which speech currents are being transmitted. A gain can therefore be obtained with lines whose impedance characteristics are so irregular that a suitable impedance balance cannot be obtained by any ordinary means. The arrangement is also useful where the repeater may be switched to any one of several lines having different impedance characteristics.

The present invention consists, in general, in the addition to one or more of the attenuation pads which are controlled by the voice-operated system, of a unit or units having a variable resistance characteristic, such as a copper-oxide rectifier, for example. The method of application and the advantages of such an arrangement will appear from the following detailed descrip-

tion, which is to be read in connection with the attached drawing. Figure 1 of the drawing shows schematically a circuit comprising one embodiment of the invention. Fig. 2 illustrates graphically some of the advantages of the proposed system.

In Fig. 1 of the drawing, the heavy lines show the essential elements of a conventional 22-type repeater, comprising the east and west networks, intended to balance the east and west lines respectively, the hybrid coils A and A', and the amplifiers B and B', interconnected by the conductors D, E, and D', E'. Such a repeater may be converted into the directional type by the addition of the amplifier-rectifiers C and C', differentially connected to the polarized relay F, which controls the subsidiary relays I and I'. These relays in turn control the pads J, K and J', K'. On the arrival of speech currents from the west line, for example, a portion of these currents is amplified and rectified through C, and flows through winding G of relay F. This winding is so poled as to make the armature of relay F take the position shown, against the left-hand contact. Current thereupon flows through biasing winding H, which is so poled as to hold relay F in that position, and through the winding of relay I, operating the latter, as indicated in the drawing. Pad K is thus disconnected from conductors E, and pad J' is connected across conductors D'. Meantime, since relay I' is not operated, pad K' is connected through the back contact of relay I' to conductors E'. Thus pads J' and K' are inserted in the lower half of the repeater, while pads J and K are removed from the upper half. Speech currents incoming from the west line will therefore be amplified and sent out on the east line. Circulating currents within the repeater, however, due to unbalances between the lines and their respective networks, will be damped out by the pads J' and K', which are designed to introduce sufficient loss to reduce such circulating currents to negligible proportions.

The current through the biasing winding H will hold the armature of relay F against its left-hand contact, even after voice currents have ceased to arrive from the west line. When the subscriber at the east end of the circuit begins to speak, however, rectified current from amplifier-rectifier C' will flow through winding G', which is opposed to windings G and H. When the current in winding G' becomes great enough to overcome the biasing flux due to the current in winding H, the armature of relay F will be

operated against the right-hand contact. This will send current through biasing winding H' , holding the armature in this position, while relay I will be released and relay I' operated. Pads J' and K' will thus be removed from the lower half of the repeater, while pads J and K will be inserted in the upper half. Gain will be provided for speech currents arriving from the east line, and objectionable circulating currents will be prevented by pads J and K . Relay F will reverse each time the direction of speech changes, so that the gain of the repeater will always be provided in the proper direction. This is the principle of the directional repeater, as covered in the patent applications already referred to.

In accordance with the present invention, I propose to include in some or all of the pads, resistance units having a variable resistance-voltage characteristic. These might conveniently take the form of copper oxide rectifiers. A pair of such rectifiers, oppositely poled to provide full-wave operation, is indicated in the drawing as included in each pad. For example, the pad K is made up of the fixed resistance L , shunted by the rectifiers M and N , oppositely poled. Polarizing batteries P and Q are shown: these may or may not be desirable. The whole combination is connected across conductors E through the transformer R . Pad L' is similarly made up of fixed resistance L' , rectifiers M' and N' , and batteries P' and Q' , all connected across the line through transformer R' . Pad J is made up of a fixed resistance, inductance and capacity in multiple, and in parallel the rectifiers S and T , connected through transformer U : no polarizing battery is shown in this case. Pad J' is similar to pad J .

The general characteristic of a pad such as has been described is that the loss which it introduces will vary with the intensity of the speech currents flowing in the circuit, the loss being greater for large currents than for small. This is an undesirable characteristic for a pad in a talking circuit, since it will tend to cause distortion by attenuating the peaks of current, such as those corresponding to vowel sounds, more than the smaller currents. It is particularly suitable to the directional repeater, however, since the pads are not in the side of the repeater which is transmitting speech, but in the opposite side, where distortion is of no consequence. Any useful speech currents which would pass through the pads would be so weak as to be practically unaffected, since any such currents that were intense enough to be appreciably affected by the pads would be sufficient to operate the relays, and remove the pads from that side of the repeater.

There are, moreover, numerous substantial advantages in the use of this type of pad in a directional repeater. In the first place, an extra degree of protection against singing will be provided, since the building up of a circulating current will be automatically checked by the increase in the loss of the pads with increase in current. Violent singing will be avoided altogether. Furthermore, some of the most objectionable effects of a near approach to the singing condition will be minimized. As is well known, when a 22-type repeater is slightly below the point of sustained singing, serious distortion is experienced due to the fact that the louder sounds of speech are accompanied by a metallic ringing sound. This is caused by circulating currents within the repeater, set up by the peaks of voice current, and sustained for an appreciable period of time because of the insufficient damping in

the circulating path. With the type of pad contemplated in the present invention, such large currents would encounter an increased loss, and the ringing sound would be much reduced. It would thus be possible to operate the repeater nearer to the point of actual singing without objectionable distortion. A useful degree of protection would be afforded against singing or the adverse effects of a near approach to singing.

In addition to furnishing this protection, the use of this type of pad will make a substantial improvement in the operation of the directional repeater. Since the relay F is differentially wound, the effective flux tending to operate it or to hold it operated depends upon the difference between the currents in the windings H and H' . On account of the poor balances that will generally exist between the lines and their respective networks, there will be considerable transmission through the hybrid coils; that is, speech currents arriving from the west line will reach amplifier-rectifier C' as well as C , and vice-versa. Unless the loss through the hybrid coils is greater than the gain in the repeater amplifiers, false operation may result. It is for this reason that the attenuation inserted in each side of the repeater is divided between two pads. The loss in the pad J' , added to the loss through the hybrid coil C' , must be at least equal to the gain of the amplifier B , in order that speech currents from the west line may hold the relay F in the position shown. Similarly, the loss in pad K' , added to the loss through the hybrid coil A , must exceed the gain of amplifier B' , otherwise speech currents from the east line will never be able to operate relay F in the reverse position. Corresponding relations will of course be necessary with respect to the pads J and K when the system is operated in the other direction.

Consider specifically the conditions necessary to permit currents from the east line to operate the relay F when it is in the position shown in the drawing. With a poor balance between the west line and its network, the loss in pad K' will have to be comparatively large to permit operation. With a fixed pad, this will mean a comparatively large loss to voice currents which are too weak to operate the device, so that initial consonant sounds of low intensity will be greatly attenuated. By using a pad constructed in accordance with this invention, such weak currents will be less attenuated, since the loss of the pad will be less for weak currents than for strong currents. This difference is illustrated in Fig. 2 of the drawing. Line A represents the flux in winding H' , increasing in direct proportion to the magnitude of the incoming current. Line B represents the flux in winding H , opposing the operation of the relay, if an ordinary fixed pad is used for K' . This flux also increases in direct proportion to the incoming current. The difference between line A and line B is the net flux tending to operate the relay: the length of the line D represents the flux necessary for operation. Line B also indicates, to an appropriate scale, the current transmitted to the west line. Line C similarly indicates the flux in winding H , and the current transmitted to the west line, when the pad K' is designed in accordance with the present invention, the proportions being such as to produce the flux necessary for operation at the same value of input current. Line C lies above line B up to the point of intersection X , since the loss of pad K' is less, for these low intensities, when designed in accordance with this

invention. Hence the magnitude of the low intensity currents transmitted to the west line is substantially greater with this type of pad than with the ordinary type.

5 Another advantage of the proposed pad may be noted from a consideration of the portions of the curves lying to the right of line D. If the currents under consideration were steady, these portions of the curves would be of no significance, 10 since relay F would operate as soon as point X was reached. Speech currents, however, are very irregular, with frequent peaks of short duration, several times as great as the average intensity of the current. It will be seen that the 15 situation with the new type of pad, indicated by line C, is considerably more favorable to the operation of the device on such short peaks than with the fixed pad, since the flux differential, represented by the difference between 20 lines A and C, is considerably greater than the corresponding difference between lines A and B for any point to the right of line D. The sensitivity of the device to speech currents, therefore, is greater with the new type of pad than with the usual type, even when the nominal sensitivity is adjusted to be the same, based on measurements made with steady single-frequency currents, as is the usual practice. The sensitivity to 25 operation from noise currents, however, will more nearly approximate the nominal sensitivity, since in general noise currents are more steady in character than speech currents, with a smaller percentage of relatively high peaks. The effective 30 sensitivity to speech currents will thus be substantially higher than that to noise currents,—a very desirable characteristic, since false operation due to noise usually represents the practical limitation on the sensitivity that can be used.

As has already been stated, it may or may not 40 be desirable to use polarizing batteries, such as P, Q, P', Q', in connection with the rectifier units. Isolated batteries of this kind are in general objectionable, if their use can be avoided. The purpose of providing them would be to have a 45 means for adjusting the magnitude of the losses introduced by the pads. The same result could be obtained to some degree by properly selecting the transformation ratios of the transformers R and R', and the magnitudes of the resistances 50 L and L'. If the transformers are arranged to step up the voltages applied to them, the losses caused by the pads will increase more rapidly with current.

Up to this point no reference has been made 55 to the effect of including rectifier units in the input pads J and J'. In many cases it will probably be undesirable to use this type of pad in these locations, since they will have a tendency to reduce the operating sensitivity of the device, 60 though they will have no effect on the differential action of the pads K, K' already explained. They may be used in some cases to improve the holding differential on the louder portions of the speech currents, if the loss of the fixed pad is not quite 65 great enough, together with the loss across the hybrid coil, to offset the gain of the repeater amplifier. This might under some conditions permit the use of smaller fixed pads, thus reducing the loss caused to currents of low intensity in the 70 direction opposite to that for which the repeater is operated.

There are numerous variations in the application 75 of the principle disclosed, which will be obvious to those skilled in the art. For example, it is well known that a four-wire system is sub-

stantially equivalent to a 22-type repeater, as indicated by the heavy lines in Fig. 1 of the drawing, except that the two hybrid sets may be located many miles apart, and several one-way amplifiers may be inserted at intervals in the four-wire lines D, E and D' E'. Circulating currents through the two sides of the four-wire circuit in tandem, due to unbalances at the hybrid sets, are objectionable in this case, as they are in the 22-type repeater. They may cause singing 10 of the four-wire system as a whole, if the terminal unbalances are severe and the intermediate gains are high. More commonly the magnitudes of the circulating currents are less than this, but they may become objectionable because of delay 15 in transmission over the long four-wire lines. Under these circumstances they produce the effect of distinct echoes of speech in the subscribers' receivers, and are hence generally known as echo currents. Voice operated devices 20 known as echo suppressors, similar in principle to the directional device herein described, are often used on such long four-wire circuits, for the purpose of introducing attenuation in the return path, and thereby reducing these circulating or 25 echo currents to small values. It is obvious from the foregoing discussion that advantages may be found in the use in such echo suppressors of pads designed in accordance with the present invention, since such pads will cause a loss to the echo 30 currents increasing with the intensity of those currents, while causing a comparatively small loss to direct transmission of insufficient intensity to operate the echo suppressor.

It should be noted that the form of the variable 35 resistance units is not limited to copper-oxide rectifiers, although the discussion has for convenience been mainly given with reference to them, but may include any units of similar characteristics. The arrangement of the units in 40 connection with the pads, moreover, is not to be considered as limited to the shunt arrangements shown, but may take a variety of forms which will be obvious to those skilled in the art. In general, while the invention has been disclosed in certain 45 specific embodiments for purposes of illustration, it will be understood that it may be embodied in other and different forms without departing from the spirit of the invention, which is defined in the appended claims.

50 What is claimed is:

1. In a two-way signaling system, the method 55 of obtaining amplification of the signals which consists in providing separate paths for the two directions of transmission, providing unidirectional amplification in each of the paths, making a continuous electrical comparison between the strengths of the signals in the two paths, and introducing in the path having the lower signal strength an attenuation varying with the 60 strength of the signal voltage in said path.

2. In a two-way telephone repeater, the method 65 of avoiding objectionable circulating currents within the repeater due to unbalances between the connected lines and their respective networks, which consists in making a continuous electrical comparison between the strengths of the signals in the two paths, and introducing in the path having the lower signal strength an attenuation varying with the strength of the signal voltage 70 in said path.

3. In a two-way signaling system, two paths 75 for transmission of signals in the two directions, a unidirectional amplifier in each of said paths, an attenuation element adapted to be inserted

- in one of said paths, electrical means for comparing the strengths of the signals in the two paths, means operated by the signals for inserting said attenuation element in the path in which the signals are weaker, and means associated with said attenuation element to give said element a loss characteristic varying with the strength of the signal voltage applied to said element.
4. In a telephone system having two unidirectional paths for transmission in the two directions, an attenuation element, voice-operated means for inserting said attenuation element in one path or the other in accordance with the direction in which telephonic currents are being transmitted, and means associated with the attenuation element for giving said element a loss characteristic varying with the strength of the telephonic voltage applied to said element from the path in which it is inserted.
5. In a two-way telephone repeater, a plurality of attenuation elements, voice-operated means for transferring one or more of said attenuation elements from one side of the repeater to the other in accordance with the direction of arrival of speech currents at the repeater, and means included in one or more of said attenuation elements for giving such element or elements a loss characteristic varying with the strength of the voltage applied thereto from the side of the repeater in which the element is inserted.
6. In a two-way telephone repeater, two paths for transmission in the two directions, a unidirectional amplifier in each of said paths, an attenuation element adapted to be inserted in one of said paths, a voice-operated device differentially connected to corresponding points in said two paths, means controlled by said voice-operated device for inserting said attenuation element in one or the other of said paths, and means associated with said attenuation element for giving said element a loss varying with the strength of the telephonic voltage applied to said element from the path in which it is inserted.
7. In a two-way signaling system, two paths for transmission of signals in the two directions, a unidirectional amplifier in each of said paths, an attenuation element adapted to be inserted in one of said paths and characterized in that its loss varies with the strength of the signal voltage applied to it from the path in which it is inserted, electrical means for comparing the strengths of the signals in the two paths, and means operated by the signals for inserting said attenuation element in the path in which the signals are weaker.
8. In a two-way telephone repeater including two paths adapted for transmission in opposite directions, the method of avoiding objectionable circulating currents within the repeater due to unbalances between the connected lines and their respective networks, which consists in varying the amplification of the two paths in accordance with the relative signal strength in the two paths, and further varying the amplification in one path in accordance with the absolute signal strength in that path.

WILLIAM H. MARTIN.
